FIG. 6

UNITED STATES PATENT OFFICE

2,227,234

EXTENSION TABLE

Irving Segal, New York, N. Y.

Refiled for abandoned application Serial No. 122,732, filed January 28, 1937. This application filed February 6, 1940, Serial No. 317,616

2 Claims. (Cl. 311—56)

This invention relates generally to extension tables and more specifically to an extension table wherein the auxiliary leaves, each operating independently, are normally concealed on each side of the table top and when either one or both are fully extended brings about a lowering of the table top to conform with the plane of the leaf or leaves.

The main object of the invention resides in the provision of an extension table whereby the auxiliary leaves are adapted to be separately extended with the minimum amount of effort and whereby when the said leaves either together or singly have been extended to their limiting position, novel means are provided to maintain the table top in elevated position until each leaf has been automatically retracted.

Another object of the invention resides in the provision of spring means to cause automatic retraction of each leaf when either one is tilted above the normal level when in extended position.

Further objects of the invention reside in the economy and simplicity of construction and simplicity of operation.

These objects and other incidental ends and advantages of the invention will hereinafter appear in the progress of the disclosure and as pointed out in the appended claims.

Accompanying this specification are drawings showing a preferred form of the invention wherein corresponding reference characters designate corresponding parts throughout the several views and wherein:

Figure 1 is a top plan view of an extension table showing the movable leaves dotted when in extended position.

Figure 2 is a transverse sectional view through the plane 2—2 of Figure 1.

Figure 3 is a sectional view similar to Figure 2 showing the intermediate position of one leaf in the automatic return thereof.

Figure 4 is a partial end elevation of Figure 3.

Figure 5 is a bottom plan view of a portion of the table top.

Figure 6 is a bottom plan of the extension table showing the movable leaves in extended position.

Figure 7 is a transverse sectional view similar to Figure 2 except that the movable leaves are shown fully extended.

Figure 8 is a sectional view corresponding to Figure 3 showing the outstretched position of the left hand leaf supported by bracket 44 and finger 49.

In accordance with the invention and in accordance with a preferred form thereof shown in

the drawings, there is provided a liftable table top 10 having a thickened periphery 10'. The inner surface of table top 10 is provided with a transverse cross bar member 36 intermediate the length of the said table top 10. The framework for the table top 10 comprises two transverse end wall members 11 and two lateral longitudinal wall members 12, table legs 13 depending from the intersections of the said wall members. The framework is provided with a longitudinal member 14 intermediate the width thereof and is supported by the upper edges of end wall members 11, the upper edges of the end wall members 11 and 12 also supporting the auxiliary leaf members 17—17. Leaf members 17—17 normally are concealed below table top 10 and are disposed on each side of member 14 the edges of the latter serving as the inner limits of the said leaf members 17—17. Member 14 proximate to each end is provided with upwardly projecting pins 15 which are received in sockets 16 provided by block members 16' depending from the undersurface of table top 10. Thus, table top 10 can be removed from the framework by lifting the same off pins 15.

Leaf members 17—17 are adapted to project from the framework when in extended position and are therefore provided with angular sliding supports. Thus one leaf is provided with two similar spaced angular sliding supports 18, 19 and the other leaf is provided with two similar spaced angular supports 20 and 21. The said supports penetrate notches 12' situated at the upper portions of the longitudinal wall members 12. The leaf members are affixed to the offset portions of the upper edge of the angular supports, the said offset portions being in a horizontal plane when the leaf members are in fully extended position as shown in Figure 7. When the leaf members 17—17 are in fully extended position, the angular supports intermediate the length rest on the bottom of the notches 12' while the lower ends of the said angular supports are provided with stops. Thus angular supports 18 and 19 are provided with end stops 22 and 23 respectively while angular supports 20 and 21 are provided with end stops 24 and 25 respectively. These stops engage with bars depending from the undersurface of member 14. Thus, stop 22 engages with bar 29, stop 23 engages with bar 35, stop 24 engages with bar 30 and stop 25 engages with bar 34. Bar 29 is supported by spaced plates 26, 27 depending from member 14, bar 30 is supported by spaced plates 27 and 28, bar 35 is supported by spaced plates 32, 33 and bar 34 is supported by spaced plates 31 and 32.

Thus, when leaf members 11-17 are in projected position, the said members are level being supported by the angular supports, the latter resting at the base of notches 12' and on the bars above mentioned. It is to be observed that while either leaf 17 is being extended toward the limiting projected position, the table top 10' is tilted upwardly thereat since the leaf rises by virtue of the rise in the angular support against the base of notch 12'. When the leaf is in fully projected position, the level thereof is above the level when in retracted or normally concealed position as shown in Figures 2 and 3. During projection of the leaf toward its limiting and extended position, the table top 10 first tilts and then falls to the level of the leaf when the latter has reached final limiting position. When either one or both leaves is in fully projected position, table top 10 rests on the same angular supports 20 as the extended leaf or leaves.

Intermediate the length of the leaf members 17-17 are pins 40 and 41 depending from the undersurface and near the outer edges, the said pins having secured thereto tension springs 38 and 39, the opposite ends of the said tension springs 38 and 39 being secured to a pin 37 depending from the undersurface of member 14 and intermediate the length thereof.

Transverse cross bar member 36 near each 30 abutment with the thickened periphery 10' of the table top 10 is provided with brackets 43 and 44, the said brackets being provided with a coil spring mounting 45. One arm of each bracket is provided with a square seat 44', while the other 35 arm is inwardly turned as at 44'', the said arms being disposed free of the transverse cross bar member 36. The turn 44'' abuts against the undersurface of cross bar member 36 thereby preventing seat 44' from touching the undersurface of table top 10. The arms of brackets 43 and 44 are normally pushed downwardly by the action of spring 45.

Thus, when leaf members 11-17 are in normal and concealed position, brackets 43 and 44 rest 45 on the upper surfaces of the leaf members. While the leaf members are projected to limiting position, table top 10 falls, guided by pins 15 and becomes coplanar with the upper surface of leaf members 11-17. If either leaf member is 50 raised when in projected position, as shown in Figure 3, the angular supports 18 and 19 become free of the bottom of notch 12', while the said supports also raise table top 10. Bracket 44 at the seat and inwardly turned portion 44' immediately engages the upper edge of the longitudinal wall 12. At this time, release of leaf 17 by the operator will cause the said leaf to drop until the angular supports 18 and 19 fall on the bases

of notches 12'. The tension of spring 39 will then draw leaf 17 inwardly. The inner edge of leaf 17 in the depressed condition will force bracket 44 against the action of spring 45 and thereby would normally cause a gradual lowering of table top 10. But such lowering is delayed by virtue of a bottom heavy and centrally pivoted finger 48, pivoting on axis 46, the said axis being affixed to the transverse wall 11 as shown in the drawings. A similar finger 49 on pivot 47 is 10 provided on the opposite transverse wall diametrically opposite.

Thus it is seen that brackets 43 and 44 and fingers 48 and 49 practically eliminate surface friction between the upper surfaces of leaf members 17-17 and the undersurface of table top 10 when retracting the leaf members from projected positions.

I wish it understood that minor changes and variations in the material, integration of parts, 20 location and subcombination of the several parts of the construction may all be resorted to without departing from the spirit of the invention and without departing from the scope of the appended claims.

I claim:

1. In an extension table, a liftably removable table top, an auxiliary leaf normally concealed in the side of said table top and oppositely movable therefrom when projecting the same, supporting arms for the said extension leaf, the said arms being movable and adapted to bring the table top to the plane of the leaf when the latter is fully projected, a spring actuated bracket secured to the underside of the table top and 35 adapted to maintain a momentary elevation induced by a lifting of the leaf and table top when the leaf is in fully projected position, and automatic means to retract the projected leaf when in the aforesaid condition of elevation. 40

2. In an extension table, a liftably removable table top, an auxiliary leaf normally concealed in the side of said table top and oppositely movable therefrom when projecting the same, supporting arms for the said extension leaf, the said arms being movable and adapted to bring the table top to the plane of the leaf when the latter is fully projected, a bracket secured to the underside of the table top and adapted to maintain a momentary elevation of both the table top and the 50 leaf induced by a lifting of the leaf and table top when the leaf is in fully projected position, automatic means to retract the projected leaf when in the aforesaid condition of elevation, and means to reduce friction between the underside 55 of the table top and the upper surface of the leaf during the act of retraction.

IRVING SEGAL.
